(57) **CLAIM**

The ornamental design for a portable pitching training mound, as shown and described.

DESCRIPTION

FIG. 1 is a perspective view of the portable pitching training mound showing my new design.

FIG. 2 is a side view thereof;

FIG. 3 is an opposite side view thereof;

FIG. 4 is a front view thereof;

FIG. 5 is a rear view thereof;

FIG. 6 is a top view thereof;

FIG. 7 is a bottom view thereof; and,

FIG. 8 is a perspective view showing the portable pitching training mound in a folded state.

The broken line showing is included for the purpose of illustration and forms no part of the claimed design.

1 Claim, 3 Drawing Sheets
